UNITED STATES PATENT OFFICE.

ADOLFO DE CLAIRMONT, OF TOLEDO, OHIO.

DEVICE FOR CLEANING EXPLOSIVE-ENGINE CYLINDERS.

1,040,147.

Specification of Letters Patent. Patented Oct. 1, 1912.

Application filed December 12, 1911. Serial No. 665,240.

To all whom it may concern:

Be it known that I, ADOLFO DE CLAIRMONT, a citizen of the United States, residing at Toledo, in the county of Lucas and State of Ohio, have invented certain new and useful Improvements in Devices for Cleaning Explosive-Engine Cylinders, of which the following is a specification.

This invention comprehends certain new and useful improvements in accessories for internal combustion engines, and has for its primary object a simple, durable and efficient construction of device which may be easily secured to the dashboard of an automobile and connected to the carbureter of the engine for the purpose of cleaning out the cylinders while they are hot and while the engine is running under its own power. And the invention also has for its object a simple and efficient device of this character which may be easily controlled by the driver of the vehicle, and used without the necessity of stopping the car, being preferably operated in a gradual manner, so that the cleaning compound used will not stall the engine and so that the fumes which necessarily result may be emitted over a comparatively long amount of mileage so as to reduce their noxious effects to a minimum. With these and other objects in view, as will more fully appear as the description proceeds, the invention consists in certain constructions and arrangements of the parts that I shall hereinafter fully describe and claim.

For a full understanding of the invention, reference is to be had to the following description and accompanying drawing, in which:

Figure 1 is a side elevation of my device, and Fig. 2 is a detail sectional view thereof.

Corresponding and like parts are referred to in the following description and indicated in all the views of the drawing by the same reference characters.

My improved device for use in cleaning out the cylinders of an internal combustion engine embodies a reservoir 1 which may be of any desired size and shape, as judgment and taste may dictate, or according to the particular requirements and size of the cylinder or cylinders for which it is designed, the reservoir 1 being provided at one end with a preferably permanently connected cap 2 and being preferably detachably connected at its other end, as by screw threads,

to the preferably flared base 3 forming an integral part of a neck 4, said neck being provided intermediate of its ends with polygonal facets 5 whereby a wrench or similar tool may be applied to this portion of the neck in the operation of applying or removing the device.

The neck 4 has a valve or cock 6 in the nature of a turn plug provided at one end with any suitable form of key 7, and the extremity of the neck is exteriorly screw-threaded, as at 8, whereby it may be conveniently attached to or detached from the adjoining end of a tube 9. The reservoir 1 is secured in any desired way to the dashboard 10 of the automobile, and to the feed pipe 9 for the cleaning fluid contained within the reservoir which leads from the reservoir to the float chamber of the carbureter 11 of the motor. Preferably, the pipe 9 is connected to the float chamber of the carbureter 11 by a valved connection 12, so that the operative communication between the reservoir 1 and the carbureter may be shut off at the carbureter when it is desired to put the cleaning device out of commission.

In use, it is to be understood that the valve 12 is normally left open and the valve 6 is opened by the driver of the car without the necessity of leaving his seat, whereby the cleaning fluid is allowed to gradually flow through the pipe 9 and drop into the carbureter in sufficient quantities to effect the cleaning operation, but not enough to stall the engine while running. At the same time, the throttle is opened as wide as it is possible to allow the liquid to be drawn up by the vacuum of the engine, together with the gasolene. As the car is run under its own power and in a heated condition, the liquid cleaner is distributed through the cylinders and tends to entirely burn out carbon, oils, etc.

Among the advantages of the device of the present invention are to be noted the following. The device can be applied or operated by the driver on the road. Furthermore, after the engine is cleaned, the car continues running and lubricates itself, for it is, of course, well known that the cleaner has a tendency to eat up the lubricating oil. Moreover, it is possible to clean the engine over a stretch of miles, distributing the fumes and the like given out by the muffler in the open air.

It is to be understood that the valve 12

may be omitted and the flow of the fluid from the reservoir 1 to the carbureter controlled entirely by the valve 6. The valve 6 is preferably formed with the square key 7, whereby an ordinary gas tank key or similar detachable handle is required to turn the valve. It is obvious that if the valve were provided with an ordinary handle, anyone could tamper with it and plug the carbureter so as to render the machine difficult to crank.

Having thus described my invention, what is claimed is:

1. The combination with a motor vehicle, including its carbureter, of a reservoir mounted upon the vehicle in accessible position, a valve connected to the reservoir and controlling the flow of liquid therefrom, and a pipe connected to said valve and to the float chamber of the carbureter.
2. The combination with a motor vehicle,

including its carbureter and dashboard, of a reservoir mounted upon the dashboard and having a pipe connection with the float chamber of the carbureter, and a valve secured to the reservoir and controlling the flow of liquid therefrom.

3. The combination with a motor vehicle, including its carbureter, of a reservoir carried by the vehicle, a pipe connection between the reservoir and the float chamber of the carbureter, a valve connected to the reservoir and controlling the flow of liquid therefrom, and another valve in the pipe at the carbureter.

In testimony whereof I affix my signature in presence of two witnesses.

ADOLFO DE CLAIRMONT. [L. S.]
